UNITED STATES PATENT OFFICE.

NATHANIEL HUGGINS, OF NEW YORK, N. Y., ASSIGNOR, BY MESNE ASSIGNMENTS, TO COPPER PRODUCTS COMPANY, A CORPORATION OF MAINE.

PROCESS AND APPARATUS FOR ELECTRODEPOSITION.

1,263,465.

Specification of Letters Patent.

Patented June 4, 1918.

Application filed April 18, 1916. Serial No. 31,866.

To all whom it may concern:

Be it known that I, NATHANIEL HUGGINS, a citizen of the United States, residing in New York, in the county of New York and State of New York, have invented certain new and useful Improvements in Processes and Apparatus for Electrodeposition, of which the following is a specification.

In forming bands or rings of copper and metals allied thereto, the processes and operations at present used are expensive; and furthermore it is practically impossible to obtain pure and extremely soft copper by the present methods of rolling, casting, turning, and trimming or grinding the same into smoothness, and size.

The object of my invention is to provide a new, simple and exceedingly cheap process, and an apparatus for carrying such process into effect, whereby metallic rings, or other small bodies may be cheaply formed by electro-deposition; and while especially adapted for use in forming the driving-band of soft copper, etc., for use on artillery projectiles to take the rifling of the cannon-bore, I do not intend to limit myself to any particular shape or contour of the article produced by my improved process, and apparatus.

Broadly my improved process, consists in substance in, (1) the forming and securing to a suitable conducting-cathode usually of brass, of a body or bodies of softer and usually more easily fusible metal or material, of high electric conductivity; which body or bodies are hereinafter, for convenience of description, designated as conducting-mold-blanks; which mold-blanks are placed within a mold of non-conducting and insulating material of the shape and contour of the article to be electrolytically produced; (2) immersing such mold, etc., in an electrolytic-bath; and by electric-deposition forming the article in such mold; (3) removing the article and conducting-mold-blank from the bath and cathode; and (4) lastly removing the conducting-mold-blank from the article either by swaging, or by melting off, or fusing, or in any other desired manner.

The apparatus for carrying said improved process into effect shown and described herein; is one for the formation of rings,

usually of comparatively pure soft copper, for any purpose, but usually used for forming banding-rings for artillery-projectiles.

My said process and apparatus for carrying the same into effect is fully shown and described in the following specification, of which the accompanying drawing forms a part, wherein similar numerals of reference designate like or equivalent parts, wherever found throughout the several views, and in which:—

Figure 1 shows in central vertical section, an electrolytic-bath receptacle or tank of the well known rectangular form, in which is revolubly mounted my improved form of revoluble cathode for the electrolytic simultaneous formation of a plurality of metallic rings; a portion of the cathode structure also being shown in like vertical cross section, in position ready to begin the electrolytic action.

Fig. 2 is an end view of such improved revolving-cathode taken in section on the line 2—2 of Fig. 1.

Fig. 3 is a side view, partially in central section, of one end of such improved-cathode; after the formation of the electrolytic-rings; and Fig. 4 is an end view in perspective of such cathode, showing certain of the produced electrolytic-rings, mold-blank-rings, and insulating-mold-rings removed, from the cathode.

Referring to the drawing:—

In Fig. 1 the reference numeral 1, designates the electrolytic-bath-receptacle, or tank containing electrolytic-liquid, usually up to the height of the line $b-b$ so as to immerse the cathode C—, to a point just below the journals thereof resting in the journal slots 2, which slots are open at the top and are formed in the end walls 3, of the receptacle. Located in the tank, usually supported on the bottom by insulating studs 4, is the anode A+, usually in the form of a plate. The cathode C—, is usually formed of brass, or other suitable metal or alloy having high electric conductivity, and consists of the central conducting-cylinder or mandrel 5, having at either end the integrally formed journals 6 and 6', removably and revolubly fitting in the journal-slots 2.

Removably secured upon the journal 6 is a pulley or gear-wheel 7, by means of which

such cathode may be rotated. The other journal 6', has in contact therewith a commutator-contact-spring 8, usually supported upon a bracket 8' on the receptacle-wall 5 leading from which spring to the minus-pole (—) 9 of the electric-generator G, is the conducting wire 10; while from the plus-pole (+) 11, an insulating conducting-wire 12, connects with the anode A+. On the 10 journal 6' is removably secured a collar 13, to prevent end thrust during rotation of the cathode.

To produce rings by my improved electrolytic process I superpose alternately upon 15 the conducting-cylinder a plurality of alternately arranged insulating mold-rings 14, of hard-rubber or other suitable insulating material, between which are interposed conducting mold-blank-rings 15, usually of lead, 20 or other comparatively soft and easily fusible metal; and when ready to be inserted in the electrolytic-bath, a peripheral annular mold space or cavity 16 of the shape and contour of the ring to be electrolytically produced, is left between the insulating-mold- 25 rings 14, upon insertion in the bath, upon turning on the current, and rotating the cathode C—, the electrolytic rings 17 required, are formed by electro-deposition 30 upon the conducting-mold-rings 15, in the annular mold-space or cavities 16, until the same are completely filled as shown in Fig. 3; whereupon the cathode is removed from the bath, the collar 13, and wheel 7, removed, 35 and all the rings forced off from the cylindrical conducting-cylinder or mandrel 5, usually by the use of a cylindrical hollow press-mandrel slipping easily over the mandrel 5. If in this operation the mold-blank- 40 rings 15, are not separated from the electrolytic rings 17, the same are then swaged off, or cut and stripped therefrom, or melted off. New conducting-mold-rings 15, and the original insulating-mold-rings 14, which can be 45 reused indefinitely are then placed upon the conducting-mandrel 5, and the operation repeated.

By this process homogeneous rings of electrolytic-copper, etc., are quickly and cheaply 50 produced, which need little if any tooling to bring about smoothness of surface and fit.

I claim:—

1. The hereinbefore described process for 55 the formation of metallic articles which consists of the following steps:—(1) forming a conducting mold-blank; (2) positioning such mold-blank upon, and in contact with a cathode; (3) positioning insulation upon the cathode to wall such mold-blank to form a 60 molding-cavity outward of such mold-blank; (4) immersing the cathode in an electrolytic bath; (5) electrolytically depositing upon the face of the conducting-mold-blank, the required quantity of deposition to form the 65 article desired to be produced; (6) removing

the conducting-mold-blank and article from the cathode; and (7) separating the mold-blank from the article.

2. The hereinbefore described process for the formation of metallic rings, which consists of the following steps:—(1) forming an annular conducting-mold-blank or a ring, or a plurality thereof; (2) positioning the same upon, and in contact with the periphery of a cylindrical-conducting-cathode; (3) interposing upon such cylindrical-cathode insulating-rings to form an annular molding-cavity outward of the peripheral surface of each of such mold-blank ring or rings; (4) immersing the cathode so supplied in an electrolytic depositing bath; (5) electrolytically depositing upon the face of the conducting-mold-blank ring or rings within the insulated rings the required quantity of deposition to form the ring or rings desired to be 85 produced; (6) removing the mold-blank-rings and electrolytically produced rings from the cathode; and (7) separating the mold-blank rings from the electrolytically deposited-rings. 90

3. The hereinbefore described process for the formation of metallic articles which consists in or comprises the following steps:—(1) forming a conducting mold-blank or blanks; (2) positioning such mold-blank upon, and 95 in contact with a cathode; (3) positioning insulation upon the cathode walling such mold-blank or blanks to form a molding-cavity or cavities outward of such mold-blank or blanks; (4) immersing the cathode in an electrolytic bath; (5) giving motion to the cathode while immersed in the bath; and during such motion electrolytically depositing upon the face of the conducting-mold-blank or blanks within the cavity or cavities, the required quantity of deposition to form the article desired to be produced; (6) removing the conducting-mold-blank or blanks and article or articles from the cathode, and, 100 (7) separating the mold-blank or blanks from the article or articles. 110

4. In a device of the class described, an electrolytic bath tank or receptacle adapted to contain electrolytic fluid; an electric-cathode located in the tank; an electric-anode also located in the tank; a conducting-mold-blank or blanks positioned on and in contact with the cathode; and walls of insulating material adjacent to the mold-blank or blanks also mounted on the cathode 120 extending beyond the mold-blank or blanks to form a deposition cavity or cavities wherein the article or articles required to be produced may be electrolytically deposited. 125

5. In a device of the class described, a receptacle adapted to receive an electrolytic fluid having journal-slots in the walls; a cathode having end-journals fitting in the journal-slots of the receptacle, adapted to be removably inserted in the receptacle so as to 130

dip into the bath; an anode in the receptacle; a source of electric-supply connected with the cathode, and the anode; and means for rotating the cathode.

- 5 6. In a device of the class described, a tank or receptacle for holding an electrolytic depositing bath; a cathode located in such receptacle removably and revolvably mounted in such receptacle; an annular conducting mold-blank-ring or rings, or a plurality thereof, located upon and in contact with the periphery of the cathode; insulat-

ing rings also mounted upon the cathode, and extending beyond the outer peripheral surface of such conducting mold-blank ring 15 or rings so as to leave a cavity or cavities of the form of the ring or rings to be deposited; a source of electrical supply connected with the cathode and anode; and means for rotating the cathode.

NATHANIEL HUGGINS.
